(57) **CLAIM**

The ornamental design for a Christmas tree stand, as shown and described.

DESCRIPTION

FIG. 1 is a front, right and top perspective view of a Christmas tree stand, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and

FIG. 8 is a front, right and top perspective view of the Christmas tree stand in use status;

FIG. 9 is a perspective view of the Christmas tree stand in other use status; and,

FIG. 10 is a perspective view of the Christmas tree stand in other use status.

The broken lines showing a tree in FIGS. 9 and 10 represent environmental subject matter only and form no part of the claimed design.

The broken lines shown in the drawings illustrate portions of the Christmas tree stand that form no part of the claimed design.
